UNITED STATES PATENT OFFICE.

EDWARD T. McCABE, OF CLEVELAND, OHIO.

STREET REGISTER OR INDICATOR.

1,409,874.

Specification of Letters Patent. Patented Mar. 14, 1922.

Application filed June 10, 1919. Serial No. 303,012.

To all whom it may concern:

Be it known that I, EDWARD T. McCABE, a citizen of the United States of America, residing at Cleveland, in the county of 5 Cuyahoga and State of Ohio, have invented new and useful Improvements in Street Registers or Indicators, of which the following is a specification.

The object of the invention is to provide 10 a simple and efficient and relatively inexpensive mechanism for use in connection with tramway and other cars for successively and automatically indicating the names of street or stations as they are respectively approached in the progress of the vehicle as a 15 means of convenience to the passengers and to avoid the necessity of having the streets or stations called by the conductor or other train men or attendants and under such conditions as to insure accuracy in the display 20 of the proper name or indication at such times or at such points relative to the progress of the vehicle as may be deemed proper and convenient regardless of the varying intervals between stations and streets or stop- 25 page points of the car.

To this end the invention consists in a construction and combination of parts of 30 which a preferred embodiment is illustrated in the accompanying drawings it being understood that changes in form, proportion and details may be resorted to within the scope of the claims without departing from the principles involved.

35 In the drawings:

Fig. 1 is a plan view in diagram to illustrate the means and arrangement of parts whereby successive impulses are given by the motive current of the railway system to the 40 station indicating apparatus contained within the car.

Fig. 2 is a view of the means whereby the impulse is conveyed from the current carrying conductors for the motive current to the 45 apparatus within the car.

Fig. 3 is a detail view of the contact carried by the car apparatus by which engagement is made with the current distributing elements located respectively adjacent to the 50 stations or stopping points of the car or vehicle.

Fig. 4 is a detail view of the station indicating apparatus located within the car.

Fig. 5 is a detail sectional view of a storage roller employed for one end of the station indicating tape.

Fig. 6 is a similar view of the means for transmitting motion from the motor to the operating drum of the indicator on the plane 6-6 of Fig. 4. 60

Fig. 7 is a similar view of the stop mechanism for limiting the movement of the operating drum on the plane 7-7 of Fig. 4.

Fig. 8 is a transverse sectional view of the tape carrying mechanism on the plane indicated by the line 8-8 of Fig. 4. 65

In Fig. 1 there is illustrated a general view of the track rails 10 trolley wires 11 and feeders 12 of a trolley car system, a car 13 being indicated in relation thereto, 70 and connected with the current carrying elements of the system there is shown a contact element 14 one of which is designed for location at a convenient distance from each station or crossing at which a car traversing 75 the track is to stop and designed to be charged with the current of the system for communication to a complementary contact element 15 in the form of a wiper adapted to be carried by the trolley pole 16 of the car as the latter in traversing the track brings its trolley wheel 17 in proximity to said charged contact. The conductor 18 by which the current received by the wiper 15 is 80 conveyed to the interior of the car is entirely 85 independent of the conductor 19 which constitutes a branch of the power circuit obtained from the contact of the trolley wheels with the trolley wire 11 and which branch is provided within the casing 20 of 90 the station indicator with a terminal 21 forming one element of a circuit closure of which the movable element 22 is carried by a plunger rod 23. The circuit of which the conductor 19 forms an element is continued 95 at 19 beyond the movable element 22 of the circuit closure to a motor 24 preferably located within the casing 20 and said circuit is a reverse switch 26 to provide for the reversal of the direction of movement of the 100 motor.

The spindle 27 of the motor is provided with a worm 28 engaging a worm gear 29 on the spindle 30 carrying an operating roll 31 105 which is arranged in operative relation with a web or tape 32 terminally attached respectively to the operating drum 33 and the storage drum 34, suitable direction rolls 35 being disposed between said drums to position a portion of the surface of the tape or web close to the plane of a display opening 110

36 in the front wall of the casing so that the name of the station exposed through said opening may be readily seen by the passengers of the car. The operating drum 33 is 5 yieldingly supported and impelled toward the surface of the operating roll 31 by means of pivotal bracket arms 37 to which may be attached an actuating spring 38. As the means for advancing the web or tape consists of the roll 31 the accumulation of the 10 web upon the drum 33 will not affect the extent of movement which, therefore, may be regulated to suit the distance between the indications or stations on the web or tape.

15 In circuit with the feed wire 18 which includes the wiper 15 is a magnet 39 of which the armature 40 is carried by the plunger 23 supporting the movable element of the circuit closure by which the motor 20 actuating the circuit is controlled, said armature normally being held yieldingly out of contact with the magnet by means of a spring 41 or the equivalent thereof.

Carried by the spindle 30 of the web or 25 tape operating roll is a stop disk 42 having a notch or seat 43 for engagement by a stop 44 carried by and consisting of a terminal of the plunger 23. When the stop is in engagement with the seat the web or tape 30 feeding roll is held in a fixed position to display a given station indicating the name through the display opening of the casing and upon the disengagement of the stop from its seat in the disk 42 the spindle of 35 the roll is free to rotate under the influence of the motor which is included in the operating circuit 19, 19^a by the movement of the circuit closure element 22 into engagement with the contact 21. The closed relation 40 of the elements of the circuit closure is maintained by the engagement of the stop 44 with the periphery 42 until the seat 43 is brought into registration with said stop whereupon the plunger is depressed by the 45 spring 41 to break the circuit between the contacts 21 and 22. The worm gear 29 is preferably engaged frictionally with the spindle 30 so that any movement of the motor spindle 27, due to inertia, after the 50 breaking of the motor circuit which is accompanied by the locking of the feed roll through the engagement of the stop 44 with the seat 23 will permit the said gear to slip on the spindle without injury to other parts 55 of the mechanism. Obviously contact 21 may be adjusted to insure the proper and effective closing of the motor circuit when the magnet is energized through the contact of the wiper 15 with the complementary 60 contact element of the power system, the energization of the magnet being accompanied by the contraction of the armature 40 and the release of the locking means by which the web or tape operating roll is normally 65 locked against movement.

The storage drum 34 is preferably provided with a storage spring 45 which is placed under tension by the unrolling of the web or tape therefrom or by the accumulation of the same upon the drum 33 70 during the movement of the web or tape in one direction and when at the end of the route the direction of the motor circuit is reversed by means of the switch 26 the movements of the feed roll in the opposite direction will remove the web or tape step by step from the drum 33 and will permit a movement of the storage drum under the tension of its actuating spring 45 to take up the web and thus rerolling it thereon. 75

It will be understood that by reason of the actuation of the indicator occurring only when the wiper 15 encounters the complementary contact for a given station or stop, and it being possible to arrange said complementary contact wherever it may be required for causing an adjustment of the indicator, the relative distances between stations is negligible as a factor in determining the efficiency of the device, and the 80 extent or the movement of the web or tape bearing the station indicating names is controlled by the circumferential extent of the disk or movable element of the stop mechanism which serves to maintain the motor circuit closed only until the proper movement of the web or tape has been secured, whereupon it is again locked and held with the web in a fixed position until the engagement of the wiper with the succeeding contact of the track system causes a further retraction of the plunger to release the stop disk and close the motor circuit. 95

The invention having been described, what is claimed as new and useful is:

1. A station indicator having a feed roll, a driving motor operatively connected therewith and provided with means for its intermittent rotation to intermittently revolve the feed roll, the casing being provided with a sight opening, a storage drum disposed within the casing above the sight opening, an operating drum disposed within the casing below the sight opening, pivotal bracket arms by which the operating drum is carried, springs yieldingly impelling the operating drum in the direction of the feed roll, direction rolls disposed respectively above and below the sight opening and adjacent that wall of the casing in which said opening is formed, and a web or tape terminally attached to the storage drum and to the operating drum and trained over the direction rolls and the feed roll in the manner and for the purpose specified. 115

2. A station indicator having a feed roll, a driving motor operatively connected therewith and provided with means for its intermittent rotation to intermittently revolve the feed roll, the casing being provided with 120

a sight opening, a storage drum disposed within the casing above the sight opening, an operating drum disposed within the casing below the sight opening and yieldingly impelled toward the feed roll, direction rolls disposed respectively above and below the sight opening and adjacent that wall of the casing in which the latter is formed, and a web or tape terminally attached to the

storage drum and the operating drum, the storage drum being provided with a storage spring whose energy is rendered potential by the unrolling of the web or tape therefrom.

In testimony whereof he affixes his signature.

EDWARD T. McCABE.
